UNITED STATES PATENT OFFICE.

WILLIAM F. BAYER, OF BUFFALO, NEW YORK, ASSIGNOR TO THE CHASE & BAKER COMPANY, OF BUFFALO, NEW YORK, A CORPORATION OF NEW YORK.

AUTOMATIC MUSICAL INSTRUMENT.

No. 921,346.

Specification of Letters Patent.

Patented May 11, 1909.

Application filed December 13, 1907. Serial No. 406,287.

To all whom it may concern:

Be it known that I, WILLIAM F. BAYER, a citizen of the United States, residing at Buffalo, in the county of Erie and State of New York, have invented a new and useful Improvement in Automatic Musical Instruments, of which the following is a specification.

This invention relates to the expression devices of pneumatically-operated musical instruments and more particularly to combined manual and self-playing pianos in which the hammer-rail is divided or sectional, so that either of the sections can be moved toward the strings independently of the other to shorten the stroke of some of the hammers, thereby subduing or softening the corresponding tones and emphasizing those produced by the remaining hammers.

The object of my invention is the provision of simple and convenient means for actuating the sections of the hammer rail.

In the accompanying drawings consisting of 3 sheets: Figure 1 is a sectional front elevation of a piano embodying the invention. Fig. 2 is an enlarged vertical section of one of the motor-pneumatics of the supplemental hammer-rail and the valve mechanism of said pneumatic. Fig. 3 is an enlarged vertical section of said valve mechanism at right angles to Fig. 2. Fig. 4 is a transverse vertical section of the instrument in line 4--4, Fig. 1. Fig. 5 is a fragmentary transverse section of the key table, on an enlarged scale, taken through the flushing valve of one of the motor-pneumatics of the hammer-rail. Fig. 6 is a fragmentary bottom plan view, on an enlarged scale, of the portion of the key-table to which said flushing valves are applied. Fig. 7 is a horizontal section in line 7--7, Fig. 5. Fig. 8 is an enlarged sectional side elevation of one of the rail-operating pneumatics. Fig. 9 is an enlarged cross section of the main and supplemental hammer-rails. Fig. 10 is a perspective view of said rails and connecting parts.

Similar letters of reference indicate like parts throughout the several views.

A indicates the case of the instrument, A¹ the key-table; A² the piano-keys; A³ the hammers of the piano-action; B the wind chest and B¹ the motor-pneumatics of the hammers. The piano action and the pneumatic action may be of any suitable or well-known construction.

D indicates the customary main hammer-rail extending continuously nearly from side to side of the case and pivoted to fixed supports D¹ by the usual arms d. This main rail has the customary upright actuating rod d² which is operated by the usual pedal, not shown, in a common manner.

E, E¹ indicate a sectional supplemental hammer-rail arranged on the rear side of the main hammer rail D and resting normally against the latter. This rail is composed of a number of independent sections, preferably two, one for the hammers of the bass and the other for those of the treble, as shown. The sections of the supplemental rail are movable toward and from the strings, and for this purpose are preferably provided with downwardly-extending arms e which are pivoted at e¹ to brackets f carried by the main hammer-rail D, as shown in Figs. 1 and 9. The supplemental rail-sections E, E¹ are swung rearwardly by independent motor-pneumatics G, G¹, preferably arranged below the key table on opposite sides of the wind-chest, as shown in Fig. 1. In the preferred construction illustrated in the drawings, the movable boards of the pneumatics G, G¹ swing vertically and are arranged below the fixed boards and these movable boards bear against buttons h mounted on upright rods or abstracts h¹. The latter are provided near their upper ends with shoulders h² which bear loosely against the underside of actuating arms I secured to the sections E, E¹ of the supplemental hammer-rail and extending forwardly therefrom, as best shown in Figs. 4 and 10. The reduced portions of the rods h¹ pass loosely through openings in the fixed supporting boards h³ of the motor-pneumatics, as shown in Fig. 8. The reduced upper ends of these rods pass through openings i of the arms I with sufficient looseness to permit the requisite swinging movement of the supplemental rail-sections. The action of the motor pneumatics G, G¹ is preferably controlled by the following mechanism:

J indicates a valve box or casing containing an upper air chamber j, a lower exhaust chamber j¹ and an intermediate valve chamber j². The upper chamber communicates with the atmosphere by an aperture k and with the valve chamber j² by a flushing port k¹. The exhaust chamber communicates with said valve chamber by an exhaust port l and with the usual main bellows L, or the

exhaust chamber (not shown) of the wind chest, by a passage l^1 and tube l^2 . The exhaust chamber j^1 contains a pouch or flexible diaphragm b^3 such as ordinarily employed in pneumatic actions. This diaphragm acts upon a stem m carrying puppet valves m^1 , m^2 arranged in the valve chamber j^2 and operating to open the exhaust port l when the flushing port k^1 is closed and vice versa, in a manner common to such actions. The motor pneumatics G , G^1 are connected with the valve-chambers j^2 of the respective valve boxes J by tubes or passages n . Leading from the chamber underneath the diaphragm b^3 of each valve box is a tube or passage o which extends upwardly to and communicates with the rear end of a flushing duct or passage p preferably arranged in a block P secured centrally to the underside of the key-table, as best shown in Figs. 5, 6 and 7. The front end of this duct opens at the bottom of the block and is normally closed by a valve q preferably carried by the free end of a spring q^1 secured at its opposite end to the underside of the key-table. This spring is depressed for opening the valve q by a push button or plunger R guided in the key-table and bearing upon the front end of the spring, as shown in Figs. 4 and 5. It will be understood that one of these buttons is provided for each of the two flushing valves p , and these buttons are preferably arranged side by side and centrally in front of the key-board, so that the two buttons may be conveniently depressed by fingers of the same hand, either simultaneously or independently.

In the operation of the instrument, when the flushing valves q are closed, as shown, the exhaust valves m^2 of the valve boxes J are also closed and the air valves m^1 are open, shutting off communication between the motor-pneumatics G , G^1 and the exhaust chambers j^1 , allowing said pneumatics to expand and permitting both sections G , G^1 of the hammer rail to rest normally against said rail, as shown in Figs. 4 and 9, and to move through their full stroke when actuated. When it is desired to subdue either the treble or the bass, the corresponding button R is depressed, thus opening the complementary flushing valve q , admitting the atmosphere under the diaphragm b^3 and raising the latter. This movement closes the air valve m^1 and opens the exhaust valve m^2 , exhausting the air from the corresponding motor pneumatic G or G^1 and causing its movable board to rise and swing the corresponding hammer-rail section backward, thereby shortening the stroke of the corresponding series of hammers. The extent of this movement of the supplemental rail-sections can be regulated by means of adjustable stops or screws s arranged on the underside of the supporting boards h^3 of the pneumatics G , G^1 in the proper position to be encountered by the mov-

able boards thereof, or by the usual arms or extensions s^1 of said boards, as shown in the drawings. The actuated section of the supplemental hammer-rail remains in its rearward position as long as the corresponding button is held down, but upon releasing the button, the flushing valve q is closed and the diaphragm b^3 descends, allowing the exhaust valve m to close and the air valve m^1 to open. The corresponding motor pneumatic is flushed and its movable board descends, allowing the actuated hammer-rail section to return to its normal position against the main hammer-rail by its own weight and by the forward or return stroke of the spring-pressed hammers B . In this manner, the tones of either the treble or the bass may be subdued to obtain the desired expression, or both buttons may be depressed simultaneously to soften the tones of both the bass and the treble. In either case, the hammer-fail sections can be actuated with great ease, as only sufficient pressure is required upon the buttons to open the flushing valves q^1 , which is comparatively little, the motor pneumatics which are controlled by said buttons effecting the rearward movements of the rail-sections. As the divided hammer-rail rests normally against the rear side of the main hammer-rail, the latter can be actuated in the ordinary manner by means of the usual pedal, not shown, when the instrument is played manually. In this case, the single or undivided main rail, when actuated, shifts both sections of the supplemental rail backward with it, shortening the stroke of all the hammers, as in pianos having a single continuous hammer-rail.

While the pneumatic action herein shown and described is preferred for controlling the motor pneumatics of the supplemental hammer rail, I do not wish to be limited to that particular construction as said action may obviously be modified without departing from the scope and spirit of my invention.

I claim as my invention:

In an instrument of the character described, the combination of a main hammer-rail, a sectional supplemental hammer-rail arranged on the rear side of the main rail, each section of the supplemental rail being provided with an actuating arm extending forwardly beyond the main rail, motor-pneumatics arranged below said rail-sections, and rods engaging said actuating arms at their upper ends and the movable members of the respective motor-pneumatics at their lower ends, substantially as set forth.

Witness my hand this 5th day of December, 1907.

WILLIAM F. BAYER.
